UNITED STATES PATENT OFFICE.

SAMUEL TURANSKY, OF BROOKLYN, NEW YORK, ASSIGNOR, BY MESNE ASSIGNMENTS,
OF ONE-HALF TO MORRIS G. HAHN, OF BROOKLYN, NEW YORK.

WATER-HEATER.

No. 862,218.

Specification of Letters Patent.

Patented Aug. 6, 1907.

Application filed August 21, 1906. Serial No. 331,433.

To all whom it may concern:

Be it known that I, SAMUEL TURANSKY, a citizen of the United States, and residing at Brooklyn, in the county of Kings and State of New York, have invented 5 certain new and useful Improvements in Water-Heaters, of which the following is a specification, such as will enable those skilled in the art to which it appertains to make and use the same.

This invention relates to devices for heating water 10 for use in bath tubs and for other purposes in which it is desired to heat water quickly; and the object thereof is to provide an improved device of this class which may be used in connection with a bath tub or in connection with any other receiver into which the water from the 15 heater flows or will flow; a further object being to provide a water heater of the class specified which is simple in construction and operation and which is also portable and may be conveniently moved from place to place and which may be applied wherever devices of this 20 kind are required.

The invention is fully disclosed in the following specification, of which the accompanying drawing forms a part, in which the separate parts of our improvement are designated by suitable reference characters in 25 each of the views, and in which;—

Figure 1 is a central vertical section of our improved water heater; and, Fig. 2 a plan view of a coil or supplemental heater which we employ.

Our invention comprises a plurality of main water 30 heating elements *a*, a supplemental heater or coil *b* placed under the main heating elements *a* and a burner *c* placed under each of the supplemental heaters or coils *b*.

In the accompanying drawing two of the main heating 35 elements *a* are shown together with two of the coils or supplemental heaters *b* and two of the burners *c*, but it will be understood that any desired number of said parts may be employed. Each of the main heating elements *a* consists of a casing composed of parallel plates 40 *a*² and a central plate *a*³, said plates being rigidly and permanently connected by rivets *a*⁴ on which are placed washers *a*⁵ whereby the plates *a*² and *a*³ are equally spaced one from the other so as to form thin spaces or chambers *a*⁶ between said plates *a*² and *a*³.

45 A water supply *b*² communicates with the bottom coil or supplemental heater *b* and at the center of said coil is an upwardly directed pipe *b*³ secured centrally in the bottom plate *a*² of the bottom main heater *a* and communicating with the bottom chamber in said bottom main heating element *a* formed by the plate *a*³, and the center of the top plate of each of the main heating 50 elements *a* is preferably raised as shown at *a*⁷ so as to form an enlarged chamber *a*⁸ in the central top portion

of said main heating elements, and a pipe *b*⁴ is secured in the central top portion of the top plate *a*² of the bottom main heating element *a* and with the next adjacent supplemental coil or heater *b* arranged thereover, and the top main heating element *a* is provided in a similar manner with a discharge pipe *d* designed to discharge the water into the tub or other receiver. 55

The burners *c* are preferably circular in form and each is provided with a gas supply pipe *c*² connected with a main gas supply pipe *c*, and each of the pipes *c*² is also provided with an air inlet pipe and regulator *c*³ similar in construction to the corresponding parts of a 60 Bunsen burner.

The operative parts of the device are inclosed by a casing *f*, and in practice the main heating elements *a* are preferably provided with depending and outwardly directed flanges *g* the edges of which are beaded as 70 shown at *g*² and fitted in corresponding beads *f*² on the casing *f*, and below the bottom burner *c* is preferably placed a transverse plate *h* which is fitted to the casing *f* in the same manner as the flanges and rims *g* of the main heating elements *a* and on which is placed a pan or receptacle *h*². 75

The bottom portion of the casing *f* is provided with air inlet ports or passages *f*³ any desired number of which may be employed and between the main heating elements *a* are other air inlet ports or passages *f*⁴, 80 and the top portion of said casing is provided with ports or passages *f*⁵ to permit of the escape of the products of combustion from said casing. The depending flanges or rims *g* of the main heating elements *a* are also provided with ports or passages *g*³ to permit the hot gases 85 or products of combustion from the burners to pass upwardly therethrough and around the main heating elements *a*, and the casing *f* is preferably provided with a handle *i* by which it may be conveniently carried when necessary. 90

In practice the pipe *d* which discharges the water from the heater is preferably left open at all times, while the pipe *d*² which supplies the water to the heater may be closed by a valve in the usual manner.

By means of this device the water is first heated in 95 the bottom or supplemental heater or coil *b* by means of the burner *c* located thereunder, and passing from the coil *b* it enters the bottom chamber of the bottom main heating element *a* and passes around the plate *a*³ therein, and then out through the pipe *b*⁴ into the next 100 upper supplemental heater or coil *b* from which it passes into the bottom portion of the next upper main heating element *a* and so on. It will be understood that the separate parts or chambers of the main heating elements *a* are of slight vertical depth, and in the above 105 described operation, or flow of the water through the

heater, said water is quickly and almost instantly heated, and in this way the required amount of water heated to the requisite temperature may be almost instantly obtained.

5 Our invention is not limited to the exact details of construction herein shown and described and especially to the manner of connecting the main heating elements *a* with the casing *f*, and it will be understood that the supplemental heaters or coils *b* may consist of any de-
10 sired number of separate coils, and water may be admitted to the bottom coil in any desired manner, and said coils and the main heating elements may also be placed in communication in any desired manner, and while we have shown and described the supplemental
15 heaters or coils *b*, it is evident that the same may, if desired, be omitted in which event the bottom and top chambers of the main heating elements *a* would be placed in communication and water supplied thereto.

In case our improved water heater is used as a port-
20 able heater to be moved from one point to another, the gas supply pipe will be provided with a flexible tube as will also the water supply pipe and the water discharge pipe, but if the heater is to be used permanently in connection with a stationary bath tub, all of said
25 connections may be permanent and the heater may be supported on a shelf adjacent to the tub or in any de-
sired manner.

Having fully described our invention, what we claim as new and desire to secure by Letters Patent, is:—

30 1. A water heater comprising a plurality of heating elements placed one above an other and composed of top and bottom plates and a central plate whereby each of said heating elements is divided into top and bottom chambers, a gas burner placed under each of said heating elements,
35 means for supplying water to the center of the bottom part of the bottom heating element, means for placing the center of the top part of each heating element in communication with the center of the bottom part of the next adjacent heating element therover, and a water discharge
40 pipe connected with the center of the top part of the top

heating element, all of said parts being inclosed in a casing.

2. A water heater of the class described, comprising a plurality of main heating elements placed one above another and each of which is composed of a top and bottom plate and a central plate dividing said main heating elements into top and bottom chambers, coils forming supplemental heating elements under each of the main heating elements, a gas burner placed under each of the water coils, said main heating elements and coils being in communication, and all of said parts being inclosed in a casing.

3. A water heater of the class described, comprising a main casing, a plurality of main water heating elements placed therein and each consisting of top and bottom plates and a central plate whereby each of said main heating elements is divided into top and bottom chambers, a water coil placed under each of the main heating elements and in communication with the bottom portion thereof, said coils being also in communication, a gas burner placed under each of said water coils, means for supplying gas to said gas burners, means for supplying water to the bottom coil, and a water discharge pipe connected with the top part of the top main heating element.

4. A water heater of the class described, comprising a plurality of main heating elements divided into top and bottom chambers which are placed in communication, a water coil placed under each of said elements, the water coil under the bottom main heating element being in communication with the central part of the bottom chamber thereof, and the coil between the separate main heating elements being in communication with the central part of the top chamber of the main heating element thereunder, and the central part of the bottom chamber of the main heating element thereover and the top chamber of the top main heating element being provided centrally with a discharge pipe, and a gas burner placed under each of said coils, all of said parts being inclosed in a casing having perforations or openings therein.

In testimony that I claim the foregoing as my invention I have signed my name in presence of the subscribing witnesses this 16th day of August 1906.

SAMUEL TURANSKY.
